UNITED STATES PATENT OFFICE.

JULIUS WÜST, OF PRAGUE, AUSTRIA-HUNGARY.

DETACHABLE SOLE FOR BOOTS OR SHOES.

SPECIFICATION forming part of Letters Patent No. 375,718, dated December 27, 1887.

Application filed May 16, 1887. Serial No. 238,362. (No model.) Patented in England April 23, 1887, No. 5,943.

To all whom it may concern:

Be it known that I, JULIUS WÜST, a subject of the Emperor of Austria-Hungary, residing at Prague, Austria-Hungary, have invented 5 certain new and useful Improvements in or relating to Detachable Soles for Boots or Shoes, of which the following is a specification.

The object of the present invention is to design a double or "clump" sole for boots or shoes, which may easily be detached or replaced by any one.

In the accompanying drawings, Figure I represents a plan of the double sole ready attached. Fig. II is a longitudinal section on line $y z$ of Fig. I. Fig. III is a cross-section on line xx of Fig. I. Fig. IV shows the double sole in plan view in the action of being attached or detached. Fig. V is a plan of the double sole with its metal strip around the edge thereof.

The letter O indicates the upper of the shoe, and D the sole, which are of the usual construction. Z indicates a metallic plate, which 25 conforms to the shape of the sole and is slightly smaller than the same. The central portion of said plate is raised, as plainly shown in Fig. IV, so as to form a depressed recess extending around the sides and front of the plate, 30 for the purpose hereinafter described. The raised portion of the plate is secured to the bottom of the sole D by means of screws a or other fastening devices, leaving the recessed edge of the plate before mentioned free.

The letter S indicates a half-sole, which has 35 secured to its upper surface a metallic frame, which conforms to the shape of the sole, and which is bent or stamped, so as to form a recessed edge around the interior portion of the 40 sides and toe, which is adapted to pass over

and interlock with the recessed edge of the plate Z, as before mentioned.

To apply the half-sole it is only necessary to slip it onto the plate Z from the front, the interlocking edges of said plate holding it in 45 place. As an additional security, the half-sole may be further fastened by a screw, d ; but this is not absolutely necessary.

It will be seen that as thus constructed the half-sole may be readily attached and detached 50 by slipping it on or off of the main sole.

In the manufacture of this article it is only necessary to number the different sizes of boots and the respective clumps, or soles to enable any one to procure the right size by 55 quoting the number and to resolve his or her boots.

This invention is also applicable to existing boots if a tongue or plate be fixed to their soles.

I claim—

The combination, with the main sole of a shoe and the metallic plate, raised at the center and having a recessed edge around its sides and toe, the raised portion of the said plate being fastened to the main sole, of the 65 half or clump sole and the metallic frame secured thereto, the said frame having a recess around the inner side and toe portions corresponding with the recessed edge of the plate and adapted to interlock therewith to secure 70 the soles to each other, substantially as specified.

In witness whereof I have hereunto signed my name in the presence of two subscribing witnesses.

JULIUS WÜST.
